UNITED STATES PATENT OFFICE.

ENRIQUE J. CONILL, OF PARIS, FRANCE.

INTERNAL-COMBUSTION ENGINE.

1,151,568.

Specification of Letters Patent. Patented Aug. 31, 1915.

Application filed November 30, 1914. Serial No. 874,594.

To all whom it may concern:

Be it known that I, ENRIQUE J. CONILL, a citizen of Cuba, residing at Paris, France, have invented certain new and useful Improvements in Internal-Combustion Engines, of which the following is a full, clear, and exact description.

This invention relates to explosion engines, particularly one for aviation adapted to drive two propellers rotating in opposite directions owing to the relative reaction between the shaft and the cylinders.

In the present invention both the crank-shaft and the cylinders revolve, but in opposite directions, around the same axis; the cranks on the crank-shaft are 180° apart in phase; the cylinders are radially disposed, spaced equiangularly, and arranged in groups or sets, one for each crank, and in each group all the pistons are connected to the same crank by means of connecting rods which are mounted side by side on the crank-pins; each cylinder is paired with a cylinder diametrically opposite in another set, the cranks to which the two cylinders of the pair are connected being 180° apart in phase; and the axial separation in the several pairs of cylinders, that is, the space or distance between the axes of the pair of cylinders is the same throughout the several groups. Moreover, all the connecting rods of the various cylinders are each arranged symmetrically relatively to the longitudinal axes of their respective cylinders, they are all alike, and are built in an exactly identical manner, so that they can be replaced at will, whenever it is considered advisable. This peculiarity considerably facilitates repairing and limits the number of spare parts which it is necessary to carry when the engine is applied to an aeroplane.

A construction according to this invention is illustrated diagrammatically in the accompanying drawing, in which—

Figure 1 is a longitudinal section, and Fig. 2 is an end view.

In the said drawing, 1, 1^a and 1^b are radial cylinders of odd number of one series, spaced equiangularly, each of the said cylinders driving directly the same crank 2 of the crank shaft 3 by means of the connecting rods e, f, g, respectively. 4, 4^a and 4^b are cylinders of odd number of a second series arranged as a star.

Each of the cylinders 4, 4^a and 4^b is diametrically opposite one of the cylinders 1,

1^a and 1^b, as shown in Fig. 2, so that the crank 5, driven by the pistons of the second series by the connecting rods h, i, k, respectively, has a phase angle of 180° relatively to the crank 2; but the cylinders 1, 1^a and 1^b on the one hand, and 4, 4^a and 4^b on the other hand are not in the same plane. The series or sets of cylinders are transversely displaced to an extent sufficient to enable their connecting rods to engage directly with the corresponding crank 2 or 5. Moreover, the cylinders of each series or set are arranged helically on the crank case 6, so that the distance d separating the axes of two diametrically opposite cylinders is constant, that is to say, that as regards the cylinders 1, 1^a and 1^b, 4, 4^a and 4^b, having connecting rods e, f, g, h, i, k, respectively, the distance between e and h is d, and it is the same between f and i and between g and k. Thus the moving masses of the pairs of pistons and connecting rods are always balanced, with the advantage that the connecting rods engage directly with the crank pins 2 and 5, which does away with the injurious oblique strains when a main connecting rod is used, and that they can be mounted by means of ball bearings on the crank pins 2 and 5. For the sake of convenience and brevity the distance d above referred to can be termed "axial separation."

Each cylinder of one series balances the forces of each cylinder of the other series, in combination with crank-balancing weights 7 and 8.

The connecting rods are exactly alike and can be arranged in a larger number than three on the same crank pin, without using an excessively heavy main connecting rod. Nor is the invention limited to two sets or series of cylinders, but the number of sets should be even.

It is to be understood that the crank-case 6 and the crank-shaft 3 rotate in opposite directions and that each drives its own propeller, not shown, for example in the manner described in my copending application Serial No. 872,567, filed November 17, 1914.

What I claim is:

1. The combination of a plurality of sets of radial cylinders arranged helically and revoluble about the same axis, each cylinder of each set being paired with a diametrically opposite cylinder of another set, the several pairs of cylinders having the same axial separation; an oppositely rotatable

crank-shaft arranged at the axis of revolution of the cylinders and having a crank for each set of cylinders, the crank for each set of cylinders having a phase difference of 5 180° from the crank for the set containing the cylinders that are diametrically paired with those of the other set; pistons working in the cylinders; and connecting rods connecting the pistons with the appropriate 10 cranks.

2. The combination of a rotary crank-shaft having a plurality of cranks 180° apart in phase; a plurality of sets of radial cylinders arranged helically and revoluble 15 around the crank-shaft in the opposite direction, one set for each crank, each cylinder of each set being diametrically opposite a cylinder of the next adjacent set, the axial separation of the pairs of cylinders which 20 are opposite each other being the same throughout the entire system of cylinders, and the number of sets of cylinders being even and the number of cylinders in each set being odd; pistons working in the cylinders; 25 and connecting rods between the pistons and the cranks.

3. The combination of a rotary crank-

shaft having two cranks 180° apart; a set of helically arranged radial cylinders spaced equiangularly and revolubly about the 30 crank-shaft and having pistons and connecting rods connected with one of the cranks; a second set of helically arranged radial cylinders spaced equiangularly and revoluble about the crank-shaft and having 35 pistons and connecting rods connected with the other crank; each cylinder of the second set being diametrically opposite one of the cylinders of the first set, providing as many pairs of cylinders as there are cylinders in each set, the axial separation of the cylinders of the several pairs being the same; the said connecting rods being all exactly alike and arranged side by side on the crank-pins of their respective cranks, and each being symmetrical with respect to the 40 axis of its cylinder.

In testimony whereof I affix my signature in the presence of two subscribing witnesses.

ENRIQUE J. CONILL.
